UNITED STATES PATENT OFFICE.

THEODORA LARSH CHASE, OF NEW YORK, N. Y.

DESIGN FOR A BOUDOIR OR PRIVATE HANDY CABINET.

Application filed June 27, 1921. Serial No. 480,932. Term of patent 7 years.

To all whom it may concern:

Be it known that I, THEODORA LARSH CHASE, a citizen of the United States, residing at New York city, in the borough of Manhattan and State of New York, have invented a new, original, and ornamental Design for a Boudoir or Private Handy Cabinet, of which the following is a specification, reference being had to the accompanying drawings, forming part thereof.

Figure 1 is a front elevation of a boudoir or private handy cabinet, showing my new design. Fig. 2 is a side elevation of the boudoir or private handy cabinet, showing my new design.

I claim:

The ornamental design for a boudoir or private handy cabinet, as shown.

THEODORA LARSH CHASE.
